[57] **CLAIM**

The ornamental design for a case for lead, as shown and described.

DESCRIPTION

FIG. 1 is a front elevational view of a case for lead showing my new design, the rear is a mirror image; FIG. 2 is a right side elevational view thereof, the left side elevational view being a mirror image thereof and, therefore, not being shown; FIG. 3 is a top plan view thereof; and, FIG. 4 is a bottom plan view thereof.

FIG. 1

FIG. 2

FIG. 3

FIG. 4
